UNITED STATES PATENT OFFICE.

EMIL SCHROEDER, OF SAN FRANCISCO, CALIFORNIA.

HAIR-CLIPPING BENCH FOR FUR-DRESSERS.

SPECIFICATION forming part of Letters Patent No. 416,864, dated December 10, 1889.

Application filed March 9, 1889. Serial No. 302,731. (No model.)

To all whom it may concern:

Be it known that I, EMIL SCHROEDER, a citizen of the United States, residing in the city and county of San Francisco, and State of California, have invented an Improved Hair-Clipping Bench for Fur-Dressers' Use, of which the following is a specification.

My invention has for its object to produce an improved clipping bench or table for the use of fur-dressers in that part of the general work of preparing skins for the furrier by which the short hairs and broken hairs lying below the fur are removed by clipping.

The construction and operation of this device is clearly explained in the following description, in which the accompanying drawings, forming part thereof, are referred to.

Figure 1 of the drawings represents the bench or table in front elevation, with the casing partly broken away to expose the inside. Fig. 2 is a view taken from the right-hand side of Fig. 1 with the casing partly broken away at the top. Fig. 3 is a top view, also partly in section; and Fig. 4 is a cross-section through the parts at the top, but on a larger scale than the other figures.

This improved bench or table is designed to hold a skin and present successive portions of its fur sides in such position that the short hairs and broken hairs standing above the fur are readily cut off close to the skin without injuring the fur, and in it provision is made for feeding or moving the skin regularly forward under a narrow aperture between the edges of two plates in such manner that the hairs to be cut are projected through the slit and stand above the plates while the fur is kept down and is protected by the plates during the operation of clipping. An endless apron, traveling over the narrow edge of a wedge-shaped bar, forms a means of moving the skin along under the plates immediately in line with the slit between them, and by drawing in the air through this aperture while the edges of the plates are held at greater or less distance apart the fur along the ridge or top edge of the bar is drawn back below the plates, leaving the hairs standing upright all along the top of the bar. One side of the case or box containing these parts is made sufficiently airtight to form an exhaust-chamber, and to

this part connection of an exhaust-fan is made by a pipe in such manner that the air from the outside is drawn in through the 55 aperture between the two plates when they are separated along the edges. One of the plates is fixed, but the other is capable of sliding laterally and can be moved back to regulate the width of the suction aperture or 60 slit while the portion of the skin lying over the ridge of the bar is being set for clipping.

A is an endless apron stretched over the wedge-shaped bar B and around a roller C under and parallel with the bar in the lower 65 part of the case.

D D are vertically-sliding boxes that carry the gudgeons C^x C^x of the roller, and E E are upright supports suitably braced and secured at the lower ends to the roller-boxes to hold 70 the wedge-shaped bar, that is fixed to their upper ends. The boxes are movable in guide-slots d d in the sides of the case G G, and coil-springs F F under the boxes serve to press up this frame and hold the wedge-shaped 75 bar up to the fixed plate.

H is a cross-bar that is part of a treadle-frame, the other members of which consist of the side levers H^x H^x, pivoted at h h inside the case and working through slots i i in the 80 front, with a foot-bar H² joining the two levers together outside. Rods or chains I I connect the boxes with the cross-bar H, and as thus arranged by pressing down the treadle-frame the bar B, with the endless apron, will 85 be drawn away from the aperture between the edges of the two plates.

K is a ratchet-wheel fixed on one of the roller-gudgeons outside, and L is a hand-lever, with a pawl L^x to engage the notches in 90 the rim of the wheel. The pawl is double and can be shifted from one side to the other of the pivot, so that the same lever will act to turn the roller either forward or backward, according to the position of the pawl. 95 This arrangement is convenient for running the apron back to fix the skin in place, as well as for moving it forward step by step over the wedge-shaped bar. An adjustable stop L², consisting of a set-screw in a bracket at one side 100 of the lever, constitutes a means of regulating the throw of the lever to give a greater or less amount of feed to the apron. The lever can be made by this means to move the

wheel K the distance of one, two, or more teeth at a single throw of the lever.

M N are the two plates lying over the bar B, of which the one M is fixed and other N is movable up or away from the fixed plate on pins or studs p p, that take through slots p'. Knobs or thumb-pieces n x n x are provided on the top of the plate N for pressing it back and drawing it forward in the operation of separating the fur and seizing the standing hairs for clipping.

The space T, inclosed by the casing G immediately under the sliding plate and along that side of the wedge-shaped bar, is separated 15 from the remaining space by the apron and the upright partitions U U, that with the back and sides of the casing form a compartment sufficiently air-tight to exclude the outside air, so that by connecting the space T with an exhaust-fan the air will almost entirely, if not altogether, be drawn in through 20 the narrow aperture between the plate N and the bar B. An inlet V in the side of the case is connected with any suitable suction apparatus—such as a small-sized exhaust-fan—by 25 a pipe W. The front of the case has a removable panel G x to give access to the apron for placing or removing a skin.

As thus constructed the bench is employed 30 and worked in the following manner: The skin to be clipped is stretched smoothly on the apron with the fur side out, and is attached across the head or leading end by hooks or pins and at the tail end by elastic tapes b b, that are provided on the apron for the purpose 35 of stretching the skin smoothly. By working the hand-lever the apron is run up until a portion of the skin rests over the ridge of the wedge-shaped bar, and when in 40 this position the sliding plate N is moved back until the aperture along this plate is of sufficient width to give the proper amount of suction. The degree of force with which the air is drawn in through this slit is regulated 45 by increasing or diminishing the space between the edges of the fixed and the movable plate, and must be only sufficient to act on the soft fur, but not to draw back the stiffer hairs, which are thus left standing 50 along the ridge of the wedge-shaped bar. While the suction is holding down the fur in this manner, the sliding plate is closed against the fixed plate and the standing

hairs are clamped between the edges. The clipping-shears are then run over the surfaces 55 of the closed plates along the line of the slit to sever the hairs. The operator now sets another portion of the skin for clipping by slightly depressing the wedge-shaped bar by pressing his foot on the treadle and then 60 turning the apron-roller by means of the hand-lever and taking his foot from the treadle. The sliding plate is then pressed back, and by this movement the slit is opened to let the coarser hairs spring past the edge 65 of the fixed plate and stand upright. The soft hair then separated and held down by the suction along the back side of the bar is covered by the plates, as before described, by drawing the sliding plate forward against the 70 edge of the fixed plate, and the fur is thus protected while the clipping is being done. In this manner the skin is run through from head to tail, and the short or broken hairs are completely and quickly removed without 75 injuring the fur.

Having thus fully described my invention, what I claim, and desire to secure by Letters Patent, is—

1. The herein-described bench or table for 80 fur-dressers' use, consisting of the case G, having an exhaust-compartment T at one side, the wedge-shaped bar B, apron A, apron-roller C, means for moving said roller to feed the apron, the inclined plate M, fixed on one 85 side of the point of bar B, and the laterally-sliding inclined plate N on the other side of said point, and pipe or conductor W, adapted to connect the exhaust-compartment with an air-exhausting apparatus, for operation as set forth.

2. In a bench or table for fur-dressers' use, the combination, with a wedge-shaped bar B, over which the skin is stretched, of the inclined plate M, fixed on one side of the point 95 of bar B, and the laterally-sliding inclined plate N on the opposite side of said point, and means by which the air is exhausted beneath said plate along one side of the wedge-shaped bar, as and for the purpose set forth. 100

In testimony that I claim the foregoing I have hereunto set my hand and seal.

EMIL SCHROEDER. [L. S.]
